UNITED STATES PATENT OFFICE

2,530,868

RECORDING DEVICE

Lovett Gareeau, Holliston, Mass.

Application March 30, 1946, Serial No. 658,425

14 Claims. (Cl. 346—112)

1

This invention relates to improvements in recording devices and is directed more particularly to devices for recording amplified thermionic impulses.

This application is a continuation, in part, of co-pending application Serial Number 417,865, filed November 4, 1941, for Electroencephalograph Devices, now Patent No. 2,409,033 dated October 8, 1946.

An object of the invention is the provision, of a recording device, operated by thermionic impulses and adapted to be used in multiple channel or single channel electroencephalographs, electrocardiographs, and for use in general purpose oscilloscopes.

A further object of the invention is the provision, of a recording device, which includes a balanced armature carried on a shaft, which is rigidly supported in spaced bearings in the device, and in which a stylus arm is pivotally secured on one end of said shaft.

A further object of the invention is the provision, in a recording device, of a movable armature and fixed pole pieces, so arranged relative to each other that the distance or air gap between the pole pieces, and the armature remains the same regardless of the deflection of the armature.

Yet another object of the invention is the provision, in a recording device, of a single shaft rigidly supported in bearings, said shaft carrying an armature intermediate the ends thereof, a stylus arm secured to said shaft adjacent to the end thereof, and an arm adjacent to the opposite end thereof, connected to opposed spring means which are in turn adjustably connected to the frame of said device.

Another object of the invention is the provision, in a recording device, of an armature shaft, carrying a recording arm, a portion of one end of which is journaled at right angles to the axis of said shaft, and including a portion angular with respect to said first portion, said recording arm including spring means constantly urging said second mentioned portion in a predetermined direction.

Another object of the invention is the provision, in a recorder, of a magnetic circuit, one leg of which includes a pair of spaced pole pieces and another leg of which includes a second pair of spaced pole pieces, the individual pole pieces carried on said first leg having notched portions in alignment with corresponding notched portion on the pole pieces carried on said second leg, said magnetic circuit including an electromagnet for polarizing said pole pieces and in which a pivoted

2

armature is carried on an axis parallel to said legs and positioned intermediate said legs and intermediate said pairs of pole pieces, and a fixed winding embracing said armature and adapted to be connected to an output anode of a thermionic circuit.

Another object of the invention is the provision, in a recorder, of a magnetic circuit, one leg of which includes a pair of spaced pole pieces and another leg of which includes a second pair of spaced pole pieces, the individual pole pieces carried on said first leg being in alignment with corresponding pole pieces carried on said second leg, said pole pieces all being slotted to form on either side of the slot thereof spaced poles of like polarity, said magnetic circuit including an electromagnet for polarizing said pole pieces and consequently said poles, and in which a pivoted armature is carried on an axis parallel to said legs and positioned intermediate said legs and intermediate said pairs of pole pieces, and a pair of fixed windings embracing said armature and adapted to be connected to the push-pull output of a thermionic device.

Yet another object of the invention is the provision of a recorder which includes a field having pole pieces and an armature cooperating therewith, said field being excited electromagnetically and including fixed windings influencing said armature, the connections for said windings being mounted on the device and terminating in a connection plug, said device being supported on a mounting plate, whereby said connection plug may be disconnected and the device bodily removed from any instrument with which it is associated.

In the aforesaid co-pending application, a recording device is shown as connected to the output of an amplifier used in connection with an electroencephalograph. The present invention relates to improvements on a recording device such as that described in the aforesaid co-pending application.

Referring to the drawings:

Figure 1 is an elevation of my new and improved recording device;

Figure 2 is a sectional elevation of my new and improved recording device as seen along the lines 2—2 of Figure 1;

Figure 3 is a view partly in section taken along the lines 3—3 of Figure 1;

Figure 4 is a fragmentary view of a portion of an electroencephalograph showing my new and improved recording device positioned therein and showing the relation of the recording device

to the tape and the means for driving the latter;

Figure 5 is a plan view of the arrangement shown in Figure 4;

Figure 6 is a fragmentary view showing the upper end of the armature and the method of securing the recording arm thereto;

Figure 7 is a diagrammatic representation of the outlet stages of a thermionic amplifier, and by way of example showing the connections to my new and improved recorder; and

Figure 8 is a circuit diagram of my new and improved recorder showing the connections terminating in a plug adapted to be plugged into the circuit shown in Figure 7.

Referring first to Figures 1, 2 and 3, a core 10, which is highly permeable magnetically, carries an electromagnetic winding 11 and this core has a central hole therein to accommodate a screw 12, and a vertical leg 13 has its lower end abutting one end of the core 10, a suitable hole 20 having been provided therein to accommodate the screw 12. A second vertical leg 14 has its lower end abutting the opposite or left end of the core 10 and the screw 12 passes through the lower ends of both legs and core, and a nut 15 and a lock washer 16 are provided for securing the core and the two legs together rigidly. The vertical legs 13 and 14 are also highly permeable, magnetically. A bar 17 of non-magnetic material adjacent to the winding 11, spans the distance 30 between the legs 13 and 14 and is secured thereto by means of screws 18. Secured on the upper end of the leg 13 is a vertical post 19 and likewise secured to the upper end of the leg 14 is a second vertical post 20. These posts are formed of non-magnetic material and are in alignment with one another on the center lines of the legs 13 and 14. A second bar 21, preferably formed of non-magnetic material, spans the posts 19 and 20 and is secured thereto. A bearing 22 is formed in the bar 17, and a bearing 23 is formed in the bar 21 and these bearings are in alignment with one another and form journals for a vertical shaft 24. Secured to the upper end of the leg 13 and extending slightly beyond the bar 21 are hexagonal posts 25 and 26. Likewise on the upper end of leg 14 are secured similar posts 27 and 28. The posts 25, 26, 27 and 28 are formed of non-magnetic material, and secured to the upper ends of these posts, by means of flat head screws 30, is a plate member 29.

The plate 29 has a clearance hole therein in alignment with the bearings 22 and 23 and through which the upper end of the shaft 24 extends. The lower end of the shaft which journals in the bearing 22 is reduced in diameter, thereby forming a shoulder which bears against the surface of the bar 17 immediately surrounding the bearing 22. On the shaft 24, beneath the bar 21, is secured a collar 31. The collar 31 may contact the bar 21, and since the shoulder contacts the bar 17 about the bearing 22, end play of the shaft is thereby eliminated. Secured to the upper end of the shaft above the plate 29, is a head boss 32. The head boss is bored out to accommodate a bushing 32a. This bushing is formed of insulating material. Its interior bore forms a snug fit on the upper end of the shaft and its exterior forms a snug fit with the bore in the head boss 32. A set screw 33, threaded into the head boss 32, bears against the insulating bushing 32a and exerts pressure on the shaft via the insulating bushing, thereby firmly securing the head boss to the shaft 24, yet enabling the shaft and the bushing to move independently of

one another in cases where undue strains are subjected to either. Several important functions of this bushing will presently be described herein.

Secured to the shaft 24 is a rectangular bar 34 which constitutes an armature. The bar 34 is preferably formed of highly permeable magnetic material yet having low retentivity and low hysteresis. Although any material having these characteristics may be used, I prefer to form my armatures from "ARMCO" magnetic ingot iron. This bar has a hole intermediate its ends to fit the shaft 24, and extending inwardly from one end thereof is a set screw 35 which engages the shaft 24.

Secured to the shaft 24 near the bearing 22 is a collar 36. The collar 36 is secured to the shaft 24 by means of a set screw 37. Threadedly engaging the collar 36 is a screw 38 having a flattened portion 39, which in turn has a hole 40 adjacent to the outer end thereof. A spring 41 has one end engaging the hole 40 and has its other end engaging a hole formed in a flattened portion 42 of a screw 43. The screw 43 extends through a hole formed in the leg 13 and by means of nuts 44 and 45 the tension of the spring 41 may be adjusted and locked in any desired adjustment. One end of a second spring 46 engages the screw 38 via the hole 40, and the other end of this spring is connected to the flattened portion 47 of a screw 48. The screw 48 extends through a hole formed in the vertical leg 14, and by means of nuts 49 and 50 the tension of the spring 46 may be adjusted and secured in any adjusted relation.

Secured to the inner face of the upper end of the leg 14 is a pole piece 51, and in alignment therewith and spaced apart therefrom is a second pole piece 52. These pole pieces and the others described below are formed of highly permeable magnetic material. The pole piece 51 has an apex 53 and formed in the apex is a slot 54 which divides the tip of the apex into two spaced hole pieces 55 and 56. The pole piece 52 is identical with the pole piece 51 and the slot in its apex is in alignment with the slot 54. Identical pole pieces, one of which is shown at 57, are secured to the vertical leg 13 near the upper end thereof, and a pole piece similar to the pole piece 52 and in alignment therewith is also secured to the upper end of the leg 13. These pole pieces are likewise provided with slots 58 like the slot 54, thereby dividing the apexes into two spaced pole pieces 59 and 60. One end of the armatures 34 is positioned in the slots 54, 58 and lies between the holes 55, 59 and the holes 56, 60. The opposite end of the armature bears the same relation to poles formed on the pole pieces 52 and the one corresponding to 57. The air gap between the upper surface of the armature and the upper pole pieces, for example 55, 59, is equal to the air gap between the lower surface of the armatures and the lower pole pieces, for example 56, 60.

The tension of the springs 41 and 46 may be adjusted so as to position the center line of the armature 34 coincident with a center line between the opposite poles (55, 59 for example).

Referring now to Figure 6, the head boss 32 has near the upper end thereof a cross-hole 61 formed therein. The recording arm 62 has an angular portion 63 journaled in the hole 61. The end of the portion 63 is threaded and a nut 64 engaging the threads retains the portion 63 in the hole 61 which forms a bearing. The recording arm has a curved portion 65, a straight

portion 66, and an angular portion 67 which may carry a stylus 68. A spring 69 has a straight portion 70 which engages a radial hole 71 formed in the boss 32. The remainder of the spring 69 embraces the curved portion 65 of the stylus and tends to urge the outer end downwardly, as seen in Figure 1. A bobbin 72, as may be seen in Figure 2, embraces the end 34^a of the armature and a second bobbin 73 embraces the end 34^b of the armature. These bobbins have spacers 74 and 75 therebetween and may be secured together by screws 76. A terminal strip 77 mounted on posts 78 and 79, mounted on the leg 14, carry terminals for the ends of the windings on the bobbins 72 and 73 and for the electro-magnet 11. The terminal strip also carries a terminal from which a wire 80 extends to the head boss 32, said wire being connected to the head boss by means of a screw 81. The connections to the terminal strip 77 will be described in connection with the circuit diagram.

The insulating bushing 32^a in the head boss 32 serves three important functions: (1) It acts as an insulator to insulate the boss 32 and the stylus from the frame of the device and consequently the potential supplied to the head boss and stylus via the wire 80 is impressed on the stylus. (2) The insulating bushing 32^a acts as a safety device to prevent undue strains which might wreck or distort the stylus arm in case the latter becomes hung up or jammed. In such cases, any urge imparted to the shaft 24 by the armature would not effect the stylus arm because if the urge were greater than the frictional urge of the bushing 32^a on the shaft, the shaft could move without moving the head boss 32 and the stylus arm 66; and (3) the operator may adjust the stylus arm in either direction to bring it to a desired zero position without having to loosen any set screws or to make any other adjustments.

The recording device, as shown in Figs. 4 and 5, is positioned in a top panel of an electroencephalograph. The recorder extends through a hole formed in the top plate 82 and is secured thereon by means of screws 83 extending through the plate member 29 on the recorder. The connections on the terminal strip 77 extend via a cable 84 to a six-pronged connector plug 85 which may be inserted in a socket (not shown) in the encephalograph. When it is desired to remove the recorder all that is necessary is to remove the screws 83, disconnect the connector plug 85, and lift the recorder out.

When the recorder is in position in the electroencephalograph its stylus 68 engages the surface of a tape 86 which is supplied from the roll of tape 87. The tape as it leaves the roll 87 passes underneath and around a knurled roller 88 which is driven by a synchronous electric motor 89. The knurled roller 88 driven by the synchronous motor is geared down so that the speed of the recorder tape past the stylus is exactly three centimeters per second.

The speed of three centimeters per second for the tape was the speed given by way of example in the aforementioned copending application. However, I do not wish to be limited to that specific speed as the tape speed can be made any value within reason. For example, I have made machines to run at a tape speed of one or two inches per hour up to speeds of forty feet per second and I have developed machines with speed changes which included gear reductions enabling the device to be set at three different speeds, and others which had continuously varia-

ble speeds. The main thing is that whatever speed is selected, it should preferably be a constant speed.

The tape mechanism is mounted on a plate 96 which carries a stud 91 upon which an arm 90 is pivotally mounted. On the end of the pivotal arm 90 is a shaft 93 upon which is mounted a roller 92. The roller 92 may have a frictionless bearing between itself and said shaft. Spring means 99 urges the arm 90 in a counter-clockwise direction, as seen in Fig. 4, and thereby urges the roller 92 against the tape and in turn urges the tape into driven relation with the knurled roller 88. The plate 96 has a depending bracket arm 100 which slides in a vertical slot 101 formed in a bracket 102 secured to the top plate 82 of the electroencephalograph. The bracket 100 has an upwardly projecting extension 97 which has a hole 98 formed therein and by means of which the tape mechanism may be pulled upwardly and removed from the instrument. The plate 96 is notched out at 103 to clear the knurled roller 88.

A cap 104 having a lateral slot 105 formed therein embraces head boss 32 and the straight portion 66 of the recording arm extends through the slot 105. Suitable screws 106 extending through a flange 107 on the cap 104 secure it to the plate member 29 and this cap serves to protect the head boss and the connection 81 between it and the wire 80 from dust and mechanical injury.

Referring now to Fig. 8, one terminal 108 of the bobbin 72 is connected to the terminal 109 on the terminal strip 77 and this in turn is connected via a wire to the prong A of the plug 85. The other terminal of the bobbin 72 is connected in common with one terminal of the bobbin 73 and these are in turn connected via a conductor 111 to a terminal 112 on the terminal strip 77, and this terminal is in turn connected via a wire 113 to the prong C and the plug 85. The other terminal of the bobbin 73 is connected via a wire 114 to a terminal 115 on the strip 77 and is in turn connected via a wire 116 to the prong B of the plug 85. The two ends of the electro-magnet winding 11 are connected to terminals 117 and 118 of the strip 77 and these are in turn respectively connected via wires 119 and 120 to prongs D and E of the plug 85.

The terminal 121 on the strip 77 is connected via a wire 122 to the prong F of the plug 85. The resistors 123 and 124, which may have substantially identical resistance values, have leads on corresponding ends thereof connected to the terminal 121. The leads from the other ends of these resistors are connected together by a jumper 125, and the wire 80 extending from the head boss 32 is connected to the jumper 125.

Referring now to Fig. 7 the push-pull output stage of an amplifier is shown together with rectifying tubes and circuits for supplying rectified D. C. potentials thereto. This output stage is substantially like that shown in application Serial No. 417,865, filed Nov. 4, 1941, now Patent No. 2,409,033, issued October 8, 1946, above referred to.

In this circuit the output tubes are indicated at 126 and 127. The plate of the tube 126 is connected via a wire 128 to the terminal A' of a multiple socket 129 adapted to be engaged by the plug 85. The plate of the tube 127 is connected via a wire 130 to the terminal B' of the socket 129, and high potential rectified D. C. from the

rectifier 131 is supplied via a wire 132 to the terminal C' of the socket 129.

It will be obvious that when the plug 85 is inserted in the socket 129 the prong A will engage A' in the socket. The prong B will engage B' and the prong C will engage C' in the socket. Therefore, potential will be supplied from C' of the socket to the prong C on the plug and via the wire 113 this potential will be impressed via 111 upon the joined terminals of the bobbins 72 and 73 and current will pass via these bobbins to the terminals 109 and 115 on the strip 77 and thence via the conductors 110 and 116, respectively to the prongs A and B and thence via the socket connections A' and the wire 128 to the plate of tube 126 and via the connection B' and the wire 130 to the plate of the tube 127.

Current for energizing the magnet winding 11 is supplied by a rectifier 133. The heaters of the tube in this rectifier are energized by the winding 134, associated with the rectifier 135 (which will presently be described). The plates of the rectifier tube in 133 are connected together and connected to one side of the source of current. A supply of current is brought in by means of a connector plug 136, and a suitable switch 137 is provided for switching the amplifier off and on. The output of the rectifier 133 is connected via wires 138 and 139 to terminals D' and E', respectively, of the socket 129, so that when the plug 85 is inserted in the socket the winding 11 is connected to this output via the wires 119 and 120.

The rectifier 135 is connected via a wire 140 to the terminal F' of the socket 129. When the plug 85 engages the socket 129, potential from the wire 140 is impressed on the wire 122 and thence to the terminal 121 on the terminal strip 77 in Fig. 8. From the terminal 121 potential goes through the divided path 123, 124 to the wire 80 and thence to the head boss 32 which carries the stylus arm 66. A variable resistance 142 is connected in series with a capacitor 143 and this array is connected across the plates of the tubes 126 and 127 and the variable resistor 142 may be varied for changing the electro-magnetic damping of the armature 34. This variable resistor acts in conjunction with the series capacitor 143 as a simple equalizing network which by means of the damping effect, reduces the tendency for the oscillograph to exaggerate its response to the natural frequency. A further effect of the network 142, 143 is to eliminate the tendency for the amplifier tubes to oscillate at a high frequency as a push-pull oscillator, by reducing the "Q" of the armature coils.

The leading of potential to the stylus via the wire 80 enables the device to be used with any type of electrically sensitive paper and by the use of such paper, the necessity for developing or otherwise treating the strip afterwards is eliminated. It will be understood, however, that any other type of stylus may be used as well on the device without departing from the spirit of the invention.

From the above it will be seen that my new and improved recording device is rugged yet sensitive, it has simple adjustments which may be locked after desired adjustments are obtained, and it constitutes a unitary structure which may be bodily applied to or removed from devices with which it is to be used.

Although I have herein shown and described, by way of example, one embodiment of the invention, it is obvious that many changes in the

arrangements shown and described may be made within the scope of the appended claims.

What is claimed is:

1. In a recording device, a shaft journaled therein, a bar of ferrous material carried on said shaft and having its axis substantially ninety degrees with the axis of said shaft, stylus means carried by said shaft, spaced poles of one polarity and spaced poles of the opposite polarity arrayed to influence one end of said bar, like poles arrayed to oppositely influence the other end of said bar, a stationary winding in said device embracing at least a portion of the length of said bar, and means to deliver electrical impulses to said winding for imparting deflecting forces to said bar.

2. In a recording device, a shaft journaled therein, a magnetizable bar forming an armature, said bar being mounted on said shaft with its axis disposed at an angle of ninety degrees with respect to the axis of said shaft, an arm pivotally mounted on said shaft, stylus means carried on said arm, spaced poles of one magnetic polarity and spaced poles of the opposite magnetic polarity arrayed to influence one end of said bar, like poles arrayed to influence the other end of said bar, and a stationary winding comprised of at least two bobbins one on each side of said shaft, both said bobbins embracing portions of the length of said bar, and means to deliver electrical impulses from the output of a push-pull amplifier to said stationary winding for inducing deflecting forces in said bar.

3. In a recording device, an electro-magnet having spaced parallel legs, pole pieces supported on said legs, a shaft between and having its axis parallel to said legs, an armature secured to said shaft and positioned in cooperative relation with said pole pieces, spaced supports on said magnet including bearings for said shaft, stationary windings embracing portions of the length of said armature for magnetically influencing the same, a stylus mounted on said shaft and adapted to be moved thereby in unison with the movement of said armature, and balanced spring means secured to said legs and acting oppositely upon said shaft for rapidly restoring said stylus to its zero position.

4. A recording device according to claim 3 in which said balanced spring means is comprised of an arm extending radially from said shaft, a pair of springs secured to said arm and extending in opposite directions, and adjustable supports secured to said legs and engaging the ends of said springs.

5. In a recording device, magnetic field means including substantially identical pole shoes each having spaced poles of like polarity, at least one of said shoes being under the influence of magnetic lines of one sign and at least another of said shoes being under the influence of magnetic lines of the opposite sign, said shoes also being so arrayed relative to one another that the spaced poles of one of them is in alignment with the spaced poles of the other with air-gaps therebetween, a pivoted armature formed of ferrous material and having the ends thereof positioned in said air-gaps, a stationary winding embracing said armature and connected to receive electrical impulses from the output of a thermionic amplifier, and a stylus operatively connected to and moved by said armature.

6. In a recording device, a magnet having parallel legs, a shaft journaled in supports on said magnet and having its axis parallel to said legs,

two pairs of pole shoes mounted on said legs and influenced thereby, each of said pairs of pole shoes being positioned with an air gap therebetween, a slot formed in each of said pole shoes to form individual poles, the individual poles of each shoe of each pair being in alignment with one another, a magnetizable bar mounted on said shaft and forming an armature, one end of said bar being positioned in the aligned slots in one of said pairs and the other end being positioned in the aligned slots in the other of said pairs, and stylus means carried by said shaft and moved in unison with the movement of said armature.

7. In a recording device, an electro-magnet having spaced parallel legs, pole pieces supported on said legs, a shaft between and having its axis parallel to said legs, an armature secured to said shaft and positioned in cooperative relation with said pole pieces, spaced supports on said magnet including bearings for said shaft, stationary windings embracing portions of the length of said armature for magnetically influencing the same, a stylus mounted on said shaft and moved thereby in unison with the movement of said armature, balanced spring means secured to said legs and acting oppositely upon said shaft for urging said stylus toward its zero position, and a conductor connected to said stylus and leading to a source of high potential direct current.

8. In a recording device, an electro-magnet having spaced parallel legs, pole pieces supported on said legs, a shaft between and having its axis parallel to said legs, an armature secured to said shaft and positioned in cooperative relation with said pole pieces, spaced supports on said magnet including bearings for said shaft, stationary windings embracing portions of the length of said armature for magnetically influencing the same, a stylus mounted on said shaft and moved thereby in unison with the movement of said armature, balanced spring means secured to said legs and acting oppositely upon said shaft for urging said stylus toward its zero position, and a connection between said stylus and a source of direct current, said connection including a limiting resistor.

9. In a recording device, an electro-magnet having spaced parallel legs, pole pieces supported in alignment on said legs, a shaft between and having its axis parallel to said legs, a bar armature secured to said shaft and having its ends influenced by said pole pieces, spaced supports on said magnet including bearings for said shaft, stationary windings embracing portions of the length of said armature for magnetically influencing the same, a stylus insulatedly mounted on said shaft and moved thereby in unison with the movement of said armature, balanced spring means acting oppositely for urging said armature toward its zero position, and means for supplying potential to said stylus.

10. In a recording device, an electro-magnet having spaced parallel legs, pole pieces supported in alignment on said legs, a shaft between and having its axis parallel to said legs, a bar-like armature secured to said shaft and positioned under the influence of said pole pieces, spaced supports on said magnet including bearings for said shaft, stationary windings embracing portions of the length of said armature for magneti-

cally influencing the same, an insulating bushing mounted on said shaft, a head boss mounted on said bushing, a set screw threadedly engaging said head boss and exerting pressure on said shaft via said insulating bushing, whereby said head boss may be frictionally moved independently of said shaft for setting purposes, and a stylus supported on said head boss and arranged to receive potential from and to be moved thereby.

11. In a recorder, a device responsive to modulated electrical impulses, said device including a shaft, an armature on said shaft, a stationary winding embracing said armature and connected to receive said impulses, a stylus arm insulatedly supported on said shaft, and means to supply potential to said stylus without electrifying the remainder of the device.

12. In a recorder, a device responsive to modulated electrical impulses, said device including a shaft, a cross-hole in said shaft, an arm having a portion thereof journaled in said hole, spring means connected to both said arm and to said shaft for urging said arm in a predetermined direction, an insulating bushing tightly fitting said shaft, a stylus support carried on said bushing, means on said support for exerting pressure on said shaft via said bushing, and a stylus carried by said support and movable therewith, whereby potential may be supplied to said support and said stylus without electrifying the remainder of said recorder.

13. In a recording device in combination, a supporting plate, a recording movement depending from said plate and having the end of a shaft extending through said plate, a movable arm mounted on the end of said shaft and extending beyond the edge of said plate, a stylus carried by said arm, and a panel having an opening therein through which said movement may

40 pass and having a movable tape adjacent to said opening, said device being adapted to be inserted in said opening, said plate being of a size to cover the opening and said stylus being of such length that it contacts said tape.

14. In a recorder, a device including an armature influenced by electrical impulses, a shaft in said device having an enlarged portion at one end thereof, a cross-hole formed in said enlarged portion, an arm having an angular portion thereof journaled in said hole, spring means connected to both the arm and to said shaft for urging said arm in a predetermined direction about the axis of said journaled portion, and a stylus carried by said arm and movable therewith.

LOVETT GARCEAU.
